MOISTENING APPARATUS FOR FLAT SURFACES

Alfred Frucki, New York, N. Y.

Application February 2, 1952, Serial No. 269,670

4 Claims. (Cl. 118—401)

1

This invention relates to dew moisteners. The conventional varieties of dew moisteners which utilize sponge, roller, etc. moistening elements, are inadequate in certain respects. For example, ordinary water sources contain corrosive acids and alkalies which ultimately cause deterioration of the material forming the moistening surface, thereby resulting in faulty operation. Moreover, in the sponge varieties, faulty operation occurs due to the accumulation of excessive moisture at the operating surface. The latter condition causes the additional inconvenience of requiring the operator to replenish the water supply too frequently. Due to the extensive open moist surfaces subject to evaporation, the water consumption in the conventional dew moistener is further accelerated.

Furthermore, no efficient provision appears in the conventional varieties to specifically wet down a large area of glue paper. Such an operation can most expeditiously and efficiently be performed by inverting the "moistener" and having it relative to the surface to be moistened. However, in the prior art devices, the "moistener" cannot be inverted without depositing an excessive quantity of water.

Consequently, the objects of this invention are to provide a device which will not be subject to the defects enumerated in the above.

More specifically, an object of this invention relates to providing a dew moistener in which moisture is brought to the operating surface at a uniform non-excessive rate.

A further inventive object relates to providing a dew moistener with a durable operating surface.

A still further object of this invention relates to providing a dew moistener which reduces evaporation losses to a minimum, and which can be safely inverted for use in connection with a large surface.

A still further object of this invention relates to the provision of a dew moistener which is in the form of an enclosed container made of non-corrosive material comprising a moistening element formed by a series of parallel closely adjacent plates, one end of which extends into a water reservoir, the other end providing a planar moist surface.

A still further object of this invention relates to providing a dew moistener of the latter type in which the moistening element has an inclined water contact area, thereby causing a more uniform feed of water to the operating surface.

Other objects and structural details will be

2

apparent from the subjoined description taken in connection with the drawings forming a part of this specification and in which:

Figure 1 is a perspective view of the moistener assembly.

Figures 2 and 3 are sectional views thru 2—2 and 3—3 as indicated in Figure 1 depicting a particular species.

Figure 4 is a view showing the mode of operation in connection with a large area.

Figure 5 is another sectional view showing a preferred form of moistening element.

Referring to Figure 2 of the drawings, the device is shown to comprise the rectangular casing 10 containing the water supply 11 and sealed at the top by the cover 12 formed centrally with the moistening element assembly 13. Obviously the casing 10 can be made in any desired shape without altering the operation. To form the assembly 13, a series of parallel plates 14 are placed closely adjacent one another extending from beneath the water surface upward thru the cover 12 to a region slightly above the outer surface of the cover 12. Thus the planar moistening surface 15 is presented externally of the casing cover 12. The small clearance between the plates produces an effect known as capillary action, the magnitude of which varies with the clearance magnitude. Consequently the quantity of water occurring at surface 15 depends upon the clearances 16. Empirically, a clearance of .006 of an inch has been found to be most desirable.

Cover 12 is formed with a depending flange shaped to snugly fit the upper periphery 18 of the casing 10. To replenish the water supply, one merely removes the cover 12 and fills the interior with water to any level desired.

Materials such as brass, aluminum, Bakelite and other "plastics" are especially desirable since the effect of corrosive agents such as acids and alkalies is reduced to a minimum. Corrosion reduction is highly desirable since a defective operating surface can render devices of this type useless. Moreover, the phenomena of capillary action is highly sensitive; thus a corroded moistening element can destroy the capillary effect.

In the form depicted in Figures 2 and 3, it should be noted that in profile the plates 13 present an inclined surface 19, leading to the vertical surface 20 connected to the bottom horizontal surface 21. By the inclination or taper of surface 19 water can more readily penetrate to all portions of the spaces between the

3

plates, thereby causing a more uniform moistening of surface 15. Moreover the taper causes the influx of water to occur at varying water levels. Since grit and sediment tend to accumulate near the casing bottom, the inclination of surface 19 tends to diminish the intake of such sediment. Such an effect is desirable since sediment can clog the clearances 16.

In the preferred form of Figure 5, the plate assembly 22 is provided with two inclined surfaces 23 and 24 leading to the vertical elongation 25. By the provision of two inclined surfaces, the beneficial effects above described are enhanced. Moreover, due to the symmetry created by the two inclined surfaces, the capillary action takes place more uniformly.

In operation, as seen in Figure 2, the object 26 to be wetted is drawn across the surface 15. The capillary effect is sufficient to cause water to be drawn to surface 15. If a larger surface is to be moistened, the device is inverted as shown in Figure 4, and drawn across the object surface 27.

It is apparent that the above described device performs the dew moistening operation efficiently, reduces evaporation losses to a minimum, is durable and can be fabricated economically and simply.

It is also desired that it be understood that numerous changes in dimension, form and material may be resorted to within the confines of the inventive concept and scope of the appended claims.

Having thus set forth and disclosed the nature of this invention, what is claimed is:

5 1. A dew moistener comprising a container with a water supply, the container being sealed by a removable cover, said cover comprising a moistening element formed by a series of parallel closely adjacent plates extending from beneath the water surface upward through the cover and projecting thereabove, presenting a smooth surface whereby water is drawn from the container interior to the said surface, the lowermost plate portions being inclined relative to the water surface.

10 2. A dew moistener as in claim 1, wherein the plates exposed to the water form an inclined surface tapering from a wide portion at the upper end, to a narrow portion at the lower end.

15 3. A dew moistener as in claim 2, wherein there are two such inclined surfaces tapering towards each other at the lower end.

20 4. A dew moistener as in claim 3, wherein the plate portions extending above the cover surface are bevelled at the edges to taper smoothly into the cover surface.
